(57) **CLAIM**

The ornamental design for a wearable electronic device, as shown and described.

DESCRIPTION

FIG. 1 is a rear perspective view of a wearable electronic device according to our new design;
FIG. 2 is a rear plan view thereof;
FIG. 3 is a front plan view thereof;
FIG. 4 is a right side view thereof;
FIG. 5 is a left side view thereof;
FIG. 6 is a top plan view thereof; and,
FIG. 7 is a bottom plan view thereof.

The shade lines indicate the character and contour of the surfaces represented, not to be confused with surface ornamentation.

The broken lines in the drawings depict portions of the wearable electronic device that form no part of the claimed design.
